UNITED STATES PATENT OFFICE.

CHARLES FRANCIS BACON, OF BROOKLINE, MASSACHUSETTS.

TORPEDO-PROTECTOR FOR BOATS.

1,271,415.

Specification of Letters Patent.

Patented July 2, 1918.

Application filed May 10, 1917. Serial No. 167,687.

To all whom it may concern:

Be it known that I, CHARLES F. BACON, citizen of the United States, residing at Brookline, in the county of Norfolk and State 5 of Massachusetts, have invented certain new and useful Improvements in Torpedo-Protectors for Boats, of which the following is a specification, reference being had therein to the accompanying drawing.

- 10 This invention relates to a system of protecting vessels from torpedo attacks and comprehends in its general characteristics a system whereby a protecting net or other articulated instrumentalities are carried or 15 supported in the water independent of the vessel, but are so connected with the vessel that they are towed and held in position for protective purposes during the rolling or 20 pitching of the vessel.
- 20 The underlying principle of the present invention is that of a series of floats having sufficient buoyancy to properly carry a suspended protecting net and to connect the floats either individually or in series with 25 the vessel in a manner that the weight of the net will be at all times carried by the floats and held in position through the connections with the vessel. Heretofore it has been customary to suspend torpedo nets from 30 booms projecting from the sides of the vessel, and to rely on the booms as a carrying means. It has also been suggested to employ a float connected with a pivoted arm or boom so that the rolling of the vessel can 35 be in a measure compensated for, such latter means, however, have been more or less ineffective requiring mechanical connections which tend to render the same more or less 40 unsatisfactory in service.

In the accompanying drawings there is shown diagrammatically a structure designed to illustrate somewhat graphically the principles of the invention presently 45 to be described. It is to be understood in this particular that the details of application and structure have purposely been omitted, as such specific details are more nearly for the artisan to develop and is un- 50 necessary for these specifications.

In the drawings:

Figure 1 is a diagrammatic side elevation of a portion of the vessel showing the application of the invention.

55 Fig. 2 is a diagrammatic plan view;

Fig. 3 is a diagrammatic cross section of one form; and

Fig. 4 is a similar view to that of Fig. 3 showing the embodiment of a preferred type or form.

The vessel is designated at A, and projecting at intervals from the side of the vessel are a series of outriggers or booms B, conveniently hinged at their rear inner edge so that when not in service they may be 60 lashed to the sides of the vessel, as shown in dotted lines, Fig. 2. These outriggers or booms may be conveniently of openwork formation and are projected by preference at right angles to the sides of the vessel. 65 They are hollow and are braced against rearward deflection by the diagonal braces or link members C. They may be extended the full length of the vessel at intervals as shown, but obviously the number required 70 will be a matter for the builder to determine and as the necessity may demand. The outer ends of the outriggers B are preferably of metal somewhat truncated in cross section as at D. The length of the outriggers are 75 such as to carry their outer ends well beyond the side of the vessel, and their hinged connections are of such a character as to sustain their weight when projected, although in this particular any suitable brace 80 strap or cable E may be employed extending to the upper bulwarks of the vessel.

As shown in Fig. 4 there is extended athwart the vessel a tubular housing F in alignment with the outriggers B, and 90 through this housing and the outriggers is extended a cable G, the same being positioned for free movement backward and forward through the housing and the outriggers. H designates a series of floats conveniently in boat form, and to the bottom of these floats there is suspended a torpedo net I. This net may be of any approved type, either chain or wire. The floats H are of such a character as to be well able to 100 support the net in its proper suspended position in the water at the side of the vessel and may be increased or diminished in number according to the requirements of service. The cables G are by preference of 105 a length sufficient to constitute tows, as shown in Fig. 1, and are connected to the forward part of the floats H so that ordinarily transverse wave action will be permitted on the floats without carrying the 110

weight of the float or the net to the outriggers. Should the vessel lurch or roll the endless cable G will remain substantially stationary, the same passing through the 5 housing or tubular member F as indicated in dotted lines, Fig. 4. This will relieve the vessel of all lifting strains and permit the floats to maintain their position on the surface of the water.

10 In Fig. 3 there is shown a somewhat modified form of structure purely diagrammatic wherein the tubular housing F' is in sections and a loop of the cable G' provided with a weight G² working in suitable vertical guides, this weight being sufficient to maintain the cable in the taut position, but not sufficient to raise or elevate the floats. Should one float by wave action be elevated 15 the weight descends to take the slack up in the cable. This general principle may be applied with weights similar to that of an elevator weight properly carried in guides, but in this particular any other convenient means may be employed for taking care of 20 the transverse wave action on the floats when it is found that the slack or length of the cable between the outriggers and the float is insufficient to compensate for the extreme 25 between the crest and the valley of the wave.

30 The general idea of a buoyed or floated torpedo protecting net so suspended that it may have a support wholly independent of the vessel and so connected with the vessel that the latter will tow the net and floats 35 the vessel being wholly free from carrying the weight, is believed to be new in this art, and while there is depicted in the drawings a diagrammatic showing of the arrangement, it is understood that various changes 40 and modifications can be made without departing from the general principle of the invention disclosed and referred to. In this connection it is evident that on vessels now in service the tubular housing may in 45 some instances be placed on the decks transversely across the same or in any other convenient location that the structure may require.

Copies of this patent may be obtained for five cents each, by addressing the "Commissioner of Patents, Washington, D. C."

The protecting apparatus when it is not necessary for use may be taken aboard the 50 vessel, the outriggers lashed to the side and ready for service when the danger zone is approached.

Having thus described generally the underlying principle of the invention and a 55 structure capable of performing the same, what is claimed as new and desired to secure by Letters Patent is:

1. A torpedo protector comprising a series of floats, a protecting element, means projecting outwardly from opposite sides of the vessel, and a flexible connection extending from one float through the vessel to the other float on the opposite side of the vessel. 60
2. A torpedo protector for vessels, a protecting element, a series of floats for supporting the element, and a tow line extending from one float to the other from opposite sides of the vessel and across the vessel. 65
3. A torpedo protector for vessels, the combination with a series of floats carrying a protecting element, of outriggers on opposite sides of the vessel in line with each other, and a cable extending from the float through the outriggers across the vessel to 70 the other float and having a free movement longitudinally. 75
4. A torpedo protector for vessels, a protecting net, a series of floats for carrying the net in the water and arranged on opposite sides of the vessel, a cable connecting the floats and extending across the vessel, and means for permitting the floats to rise and fall on the lateral wave action for taking up the slack of the cable under such 80 conditions. 85
5. In a torpedo protector for boats, a protecting element, a series of floats carrying the same, hinged outriggers at the side of the vessel, cables connected with the floats 90 extending through the outriggers and across the vessel to the opposite float, substantially as described.

In testimony whereof I hereunto affix my signature.

CHARLES FRANCIS BACON.
